Specification for Design.

Patented Dec. 16, 1913.

Application filed August 13, 1913. Serial No. 784,613. Term of patent 14 years.

To all whom it may concern:

Be it known that I, HARRISON HURLBERT BOYCE, a citizen of the United States, residing at Forest Hills, in the county of Queens and State of New York, have invented a new, original, and ornamental Design for a Temperature-Indicator, of which the following is a specification, reference being had to the accompanying drawings, forming a part thereof.

Referring to the annexed sheet drawing, Figure 1, represents a front elevation of my design for a temperature indicator, made

in accordance with my invention, Fig. 2 is a rear view thereof, and Fig. 3 is a view in perspective.

I claim—

The ornamental design for a temperature indicator as shown.

In witness whereof I have hereunto set my hand in the presence of two subscribing witnesses, this 18th day of July, 1913.

HARRISON HURLBERT BOYCE.
